LUMINAIRE

George P. Wakefield, Vermilion, Ohio, assignor, by mesne assignments, to The Wakefield Corporation, Detroit, Mich., a corporation of Michigan

Filed Nov. 8, 1960, Ser. No. 62,762

Term of patent 14 years

(Cl. D48—23)

FIG 1

FIG 2

FIG 3

FIG. 1 is a perspective view of a luminaire showing my new design from one of its duplicate ends;

FIG. 2 is a much enlarged fragmentary vertical cross-section view taken substantially along the line 2—2, FIG. 1 of the luminaire refractor; and

FIG. 3 is an enlarged fragmentary bottom plan view as viewed upwardly in FIG. 2.

The side and end not shown in FIG. 1 are the same, respectively, as the side and end appearing therein.

The end of the luminaire as shown in FIG. 1 is shaded to show contrast.

I claim:

The ornamental design for a luminaire, as shown and described.
